CLOCK CASE

Filed July 7, 1933

Inventor:
Harriet Heile,
by Harry E. Dunham,
Her Attorney.

UNITED STATES PATENT OFFICE

91,240

DESIGN FOR A CLOCK CASE

Harriet Heile, Chicago, Ill., assignor, by mesne assignments, to Warren Telechron Company, a corporation of Maine

Application July 7, 1933. Serial No. 48,655

Term of patent 14 years

To all whom it may concern:

Be it known that I, HARRIET HEILE, a citizen of the United States, residing at Chicago, in the county of Cook, State of Illinois, have invented a new, original, and ornamental Design for a Clock Case, of which the following is a specification, reference being had to the accompanying drawing forming a part thereof. The figure is a front perspective view of a clock case showing my new design.

I claim:

The ornamental design for a clock case as shown.

In witness whereof, I have hereunto set my hand.

HARRIET HEILE.
